UNITED STATES PATENT OFFICE.

STERLING T. PLAYFORD, OF CASSOPOLIS, MICHIGAN.

TILE.

SPECIFICATION forming part of Letters Patent No. 738,627, dated September 8, 1903.

Application filed December 16, 1902. Serial No. 135,457. (No model.)

To all whom it may concern:

Be it known that I, STERLING T. PLAYFORD, a citizen of the United States, residing at Cassopolis, in the county of Cass and State of Michigan, have invented a new and useful Tile, of which the following is a specification.

This invention relates to certain improvements in tiles or blocks formed of cement or other materials.

10 The principal object of the invention is to provide an improved building-tile principally intended for roofing purposes and which may be used to advantage for sidings and other purposes.

15 A further object of the invention is to provide a tile of such construction as to permit of the sagging or settling of a roof or other surface on which it may be employed without danger of breaking the tiling or destroying 20 or impairing the joints between the adjacent tiles.

A still further object of the invention is to provide a construction of tile which will permit of the formation of an elastic but water- 25 proof joint and in which the joining edges of the tiles are so arranged as to provide for securely holding the joining material in place.

A still further object of the invention is to provide the tile with a fastening means so arranged that the position of the fastening 30 means may be altered to some extent in accordance with the character of the surface to which the tile is to be secured.

A still further object of the invention is to 35 provide a construction of tile which will permit of the ready removal of any one tile without danger of destroying the adjacent tiles in the event of breakage, and, further, to provide an improved anchoring or securing means 40 for connecting adjacent tiles to each other.

With these and other objects in view the invention consists of the novel construction and arrangement of parts hereinafter described, illustrated in the accompanying drawings, and particularly pointed out in the appended claims, it being understood that various changes in the form, proportions, size, and minor details of the structure may be made without departing from the spirit or 45 50 sacrificing any of the advantages of the invention.

In the accompanying drawings, Figure 1 is

a perspective view of a tile constructed in accordance with the invention. Fig. 2 is a similar view of the rear or under face of said tile. 55 Fig. 3 is a detail sectional view showing a number of tiles constructed and arranged in accordance with the invention. Fig. 4 is a similar view showing the anchoring means which may be employed for connecting adjacent tiles to each other. Figs. 5 and 6 are detail sectional views, on an enlarged scale, illustrating more clearly the construction of the joints and securing means.

Similar numerals of reference are employed 65 to indicate corresponding parts throughout the several figures of the drawings.

The tiles forming the subject of the present invention are formed of cement or any suitable composition of material into which cement enters as an ingredient or binding agent, the tiles being of any desired contour—either square, oblong, hexagonal, or of other form, as may be required—and their outer faces may be either plain or ornamented in any desired manner. The tiles are preferably provided at a central point with a sheet of wire gauze or netting 1, which material adds to the strength of the tile and permits of considerable reduction in its thickness without decrease in strength.

The edge of each tile is of the contour more clearly shown in Figs. 5 and 6, being inclined inwardly from the lower edge, as indicated at 3, to a point near the upper surface of the tile, and thence being rounded or inclined, as indicated at 4, in an opposite direction, so that between the edges of two adjacent tiles there is formed a tapering slot having its widest portion at a point below the outer or upper surface of the tile in order to insure the retention of the joining or binding material. The lower or inner edges of the tiles are preferably abutting, and after the tiles are in place the joint is calked by the introduction of oakum or similar material, as indicated at 5, the material being introduced by calking-irons in the usual manner and terminating at a point below the outer surface of the tile. To preserve the oakum, a layer of asphalt 6 or paint or other suitable preservative material, preferably of an elastic or semielastic nature, is placed on top of the oakum, but without filling the whole of

the joint. On the top of the asphalt or other material is placed a layer of cement or other binding agent, as indicated at 7, this binding agent being introduced between the curved convergent walls of the tile so that a wedge-like joint is formed, which will under all circumstances prevent the escape of such material.

In each tile, preferably at a point near each of the corners, is formed an opening 8 for the passage of a securing device, such as a nail or screw, a nail being generally employed in practice. These openings are oblong on the face of the tile, and the longer sides converge toward the inner face of the tile to form a tapering opening through which the nail may be driven, the length of the opening permitting the adjustment of the nail to such position as may be necessary in order to avoid cracks or obstructions to the passage of the nail. When the tiles are secured in position, the openings are filled with cement or like material to assist in holding the nail in place and preserve the same from oxidation as well as to conceal the nail end, the cement used being of a character similar to that forming the body of the tile in order not to detract from the appearance of the surface, especially where the tiling is used to form an ornamental siding for a building.

In roofing it is not absolutely necessary that the tiles be secured in place, but in general practice it is advisable to provide means for securing them to each other, and for this purpose the edge portions of the tiles are recessed, as indicated at 8, for the reception of bonding bars or anchors 9, which may be formed of sections of wire or rods having upwardly-bent end portions adapted to engage in the recesses of the tiles, and thus secure adjacent tiles to each other.

The construction is such as to permit considerable movement of the roof or other surface on which the tiles are placed without

danger of breaking the tiles, the joining material being elastic and compressible, so that the surface may become uneven and irregular and still prevent the passage of water.

After the tiles are placed in position the whole surface may be painted, cemented, or otherwise finished in order to preserve the tiles and render the joints waterproof. The construction is such as to readily permit the removal of a broken or damaged tile without interfering with the adjacent tiles, and a new tile may be placed in position and calked more readily than in tiles having interengaging joints.

Having thus described the invention, what is claimed is—

1. A tile having its inner or rear surface of greater area than its outer surface so that the inner portions of the edges of adjacent tiles may come into contact, the edges of the tile being recessed, and said recesses extending 65 from the inner to the outer surfaces of the tile and having their greatest depth at a point between the two faces of said tile.

2. A tile provided with an opening for the passage of a securing means, said opening being oblong in general contour and its longer walls converging toward the rear face of the tile to form engaging surfaces for the securing means.

3. A tile having bonding recesses in its 75 under surface and provided with a plurality of tapering openings for the reception of securing means, the edges of the tile being recessed for the reception of a joining or bonding material.

In testimony that I claim the foregoing as my own I have hereto affixed my signature in the presence of two witnesses.

STERLING T. PLAYFORD.
